Mass., assignors to United Shoe Machinery
Corporation, Flemington, N. J., a corporation of
New Jersey

Application October 26, 1949, Serial No. 123,614

12 Claims. (Cl. 144—93)

1

This invention relates to machines for forming in heels bores extending heightwise through said heels and serving as passages through which thermoplastic resin is injected for use in the attachment of the heels to shoes in accordance with the method disclosed in United States Letters Patent No. 2,600,507, granted June 17, 1952, on an application filed in our names.

The present invention consists in the novel features hereinafter disclosed, reference being had to the accompanying drawings which illustrate embodiments of the invention selected for purposes of illustration, said invention being fully disclosed in the following description and claims.

In the accompanying drawings,

Fig. 1 is a side view, partly broken away, of an illustrative heel drilling machine;

Fig. 2 shows an enlarged front view on the line II—II of Fig. 1;

Fig. 3 is a view on the line III—III of Fig. 2 showing a heel positioned and clamped in the machine ready to be drilled;

Figs. 4 and 5 are views on the lines IV—IV and V—V respectively of Fig. 3 showing heel engaging platens of the machine;

Fig. 6 is a section on the line VI—VI of Fig. 2 showing a drilled Cuban heel, which has been covered and has attached to it a top lift, positioned and clamped in the machine preparatory to forming in the top lift a bore or passage which registers with a previously formed bore or passage in the heel;

Fig. 7 shows in perspective a Cuban heel which has been bored by the use of the present machine and has also been slotted by the use of another machine preparatory to attaching the heel to a shoe by practicing the method disclosed in said Patent No. 2,600,507;

Fig. 8 is an illustrative view showing in side elevation three Cuban heels which have a common base and are of different heights and which have been drilled by the use of the present machine; and

Fig. 9 shows a lengthwise median section through a Louis heel which has been drilled by the present machine.

The illustrative machine will be described with reference to drilling Cuban heels 20 (Figs. 1, 3, 6, 7 and 8) preparatory to attaching the heels to shoes (not shown) by practising the method disclosed in said Patent No. 2,600,507. The heels 20 at the time they are attached to the shoes commonly have formed in their attaching faces 22 (Figs. 6, 7 and 8) pairs of slots 24 (Fig. 7) which intersect and have the general appearance

2

of a letter X. As explained in said Patent No. 2,600,507, after the heel 20 has been forced with heavy pressure against a heel seat of the shoe, viscous thermoplastic resin is forced by the use of an injector or "gun" (not shown) through a passage or bore 26 in the heel and into the slots 24 as well as into voids (not shown) formed between the heel and the heel seat of the shoe and into undercut cavities (not shown) in said heel seat, the resin filling up the voids, cavities and slots and substantially the entire passage 26. The heel 20 is held under pressure against the heel seat of the shoe until the resin has cooled, shrunk slightly and hardened, the shoe, including the heel, which is then permanently secured to the shoe, thereafter being removed from the machine.

The illustrative machine comprises drilling mechanism 28 (Fig. 1) which is adjustably secured to posts 30 (only one shown) fixed at their lower ends to a base 32 (Figs. 1 and 2) and which is operated by any suitable source of power, for example an electric motor (not shown), said mechanism comprising a rotary drill 34 (Figs. 1, 2, 3 and 6) mounted for vertical reciprocation lengthwise of a vertical axis 36 of rotation. The rotary drill 34 may be moved lengthwise of the axis 36 by swinging an arm 38 (Fig. 1) having secured to it a pinion 40 which is rotatably mounted in a drill mechanism housing 42 and is geared to a rack portion of a quill 44 movable along a vertical guideway 46 of said housing. Mounted for rotation in ball bearings carried by the quill 44 is a spindle or shaft 50 to the lower end of which is secured a chuck 52 in which the drill 34 is removably secured.

It is desirable to orient and in most instances to centralize the attaching face 22 and a tread face 54 of the heel 20 with relation to said axis 36 and also to secure the heel thus positioned against movement. Accordingly, the machine comprises a drill jig 56 for quickly and effectively positioning the heel and clamping it preparatory to forming the passage 26. It is also desirable that the slots 24 shall cross each other approximately at the center of the attaching face 22 of the heel and that the inner end of the passage 26 shall "break out" or terminate at the bottom of the intersecting portions of the slots, the outer end of said passage terminating approximately at the central portion of the tread face 54 of the heel. The inner end of the passage 26 at the intersecting slots 24 is located at the transverse center of the attaching face 22 of the heel but is usually located somewhat forward of

the longitudinal center of said face. Were the passage 26 extended to a plane of a rim 58 (Figs. 7 and 8) of the attaching face 22 of the heel 20 the axis of said passage would pass substantially through the longitudinal and transverse center of the plane surface defined by said rim.

Heels to be drilled are of various sizes and styles and it is common practice to vary in accordance with the style of the heel the depth of the slots 24 as well as the angle 60 (Fig. 7) at which the slots are disposed to each other and the positions of the slots longitudinally of the attaching face of the heel. Moreover it is sometimes desirable in preparing Cuban heels 62 for attachment to shoes by the above-mentioned method that the intersecting portions of the slots 24 shall be located slightly further rearward of the attaching face of the heel than they would be located in a Cuban heel having an attaching face of the same length as that of the attaching face of such Cuban heel. Since the heights and the back angles 72 of Cuban heels 20 vary it will be apparent that central points 74, 76 of the tread face 54 and the planes defined by the rims of the attaching faces of the heels are offset different distances 78 longitudinally of the heel from each other. Moreover, the plane of the tread face 54 and the plane of the rim 58 of the attaching face 66 of the heel may be approximately parallel to each other, as in the case of some Cuban heels or may be inclined at a considerable angle to one another as they are in the case of extremely high heels.

It is desirable that the outer end of the passage 26 shall be located at the central part of the tread face of the heel and that the inner end of said passage shall open into the intersecting portions of the slots 24. With the foregoing considerations in view the drill jig 56 is provided so that the operator may quickly and effectively position and clamp heels of all sizes and/or styles in the heel drilling machine. The machine will be described with reference to Cuban heels and as will be hereinafter explained is provided with special adjustments which are useful in adapting the machine for operation upon Louis heels. The drill jig 56 of the machine comprises a main frame 80 secured by bolt and nut combinations 82 (Fig. 1) to the base 32. Secured by screws 84 (Fig. 2) to spaced upstanding side plates 86 of the main frame 80 is a header 88 having a cylindrical recess 90 in which fits a bushing or guide 92 having a bore or guideway 94 the axis of which is coincident with the axis 36 of the drill 34. The drill 34 fits slidably in the bushing 92 which is secured in a desired position in the header 88 by a setscrew 96.

The upstanding side plates 86 of the main frame 80 have aligned bores 98 in which are secured by screws 100 bearing pins 102. Secured by screws 104 (Figs. 2 and 4) to a tread platen or plate 106 are lugs 108 which are pivotally mounted upon the bearing pins 102. Fixed to the main frame 80 of the drill jig 56 are upstanding guide rods or guides 110 (Figs. 1, 2 and 5) upon which is slidably mounted for translatory movement a yoke or carrier 112 pivotally connected by a pin 114 to a two-part rod 116 which comprises a turnbuckle 118 (Fig. 1) and is pivoted to a treadle 120. The treadle 120 is fulcrumed at its rear end upon a bearing pin 122 secured to an angle bracket 124 fixed by screws 126 to a lower portion of a bench 128 upon which the drilling machine is mounted. The treadle 120, and accordingly the carrier 112, are con-

stantly urged upward by a spring 130, upper and lower ends of which are attached respectively to a hook attached to the bench 128 and to the treadle, upward movement of the treadle being limited by engagement of the carrier with leather stops 132 (Fig. 2) secured to the rods 110.

Secured by screws 134 to the carrier 112 are bearing pins 136 upon which are pivotally mounted lugs 138 secured by screws 140 (Figs. 2 and 5) to a lower platen 142, said platen being free to pivot upon the carrier. The platen 142 is so weighted that it constantly tends to tilt clockwise as viewed in Figs. 1 and 3, such movement being limited when there is no work in the machine by its engagement with the upper platen or with a stop 143 (Fig. 2). The upper or tread platen 106 tends to swing or tilt counterclockwise as viewed in Fig. 1, such swing movement being limited by the engagement of the platen with a stop 144 secured to one of the side plates 86.

Force-pressed into the platens 106, 142, which may be described as being independently tiltable or pivoted, are bearing collars 146, 148 (Figs. 3, 4 and 6) respectively having formed in them bores 150, 152 which are in alignment with the guide 92 and through which the drill 34 passes in operating upon the heel. The collars 146, 148 may be considered as parts of their associated platens 106, 142, the bores 150, 152 in the collars being sufficiently large to enable the drill to pass through the platens without interference irrespective of the angle at which the platens are tilted.

As will be explained later, after moving side, rear and breast abutments or gages 154, 156 and 158, respectively, to open or retracted positions the heel 20 in which the resin receiving passage 26 is to be formed is presented manually to the jig 56 by forcing the tread face 54 of the heel 20 against portions of a flat lower surface 160 of the collar 146 of the platen 106, the tread face of the heel, after said abutments have been released to permit them to move under spring action to their gaging positions, being oriented widthwise and lengthwise by said abutments. The lower face 160 of the collar 146 and a lower face 162 of the platen 106 are in alignment and will be referred to as the heel engaging face 160, 162 of the platen. A horizontal axis 164 of the pivot pins 102 extends along the lower surface 160, 162 of the platen 106 and is arranged at right angles to the vertical axis 36 lengthwise of which the drill 34 is reciprocated.

The side abutments 154 are secured by reversed screws and shoulder screws 168, (Fig. 4), 170 (Figs. 3 and 4), respectively, to blocks 172 which overlie the platen 106 and have depending ribs slidably fitting in corresponding slots 173 formed in the platen. Work engaging portions or faces of the side abutments 154 are disposed at right angles to the surface 160, 162 of the platen 106 and engage the sides of the heel adjacent to its tread face 54. The breast and rear abutments 158, 156 are secured by reversely arranged screws and shoulder screws 174, 176 to blocks 178, 180, respectively, which overlie the upper face of the platen 106 and have depending ribs slidably fitting in slots 182, 184 formed in said platen. A work engaging face 186 of the breast abutment 158 is elongated so as to extend, in Cuban work, against the lower breast edges of the heels. A work engaging face 188 of the rear abutment 156 is narrow, concaved laterally and extends downward to a considerable extent for a purpose which will be hereinafter explained.

Rotatably mounted upon the collar 146 are upper and lower carriers 190, 192 (Figs. 3, 4 and 6) having pairs of arms 194, 196, respectively, which are operatively connected through links 198, 200 and the shoulder screws 176, 178 to the side abutments 154 and to the rear and breast abutments 158, 156. The side abutments 154 on the one hand and the breast and rear abutments 158, 156 on the other hand are constantly urged as units to their closed or inner positions along their respective slots 173 and 182, 184 by springs 202, 204 which have their outer ends attached to studs 206, 208 secured to the platen 106 and have their inner ends secured to studs which connect one of each of the arms 194, 196 to an associated link 198, 200. Mounted upon the carrier 192 is a stud 210 and formed upon the carrier 190 adjacent to the stud is a shoulder 212. In order to open up the side abutments 154 and the breast and rear abutments 158, 156 to insert the tread end portion of the heel 20 against the face 160, 162 of the platen 106, the shoulder screw 176, which pivotally connects the link 198 to the abutment 156, has threaded onto it an upstanding handle 214 which may be gripped by the operator. With the above construction it will be apparent that when the handle 214 is slid to the right, as viewed in Figs. 1, 3 and 4, the shoulder 212 acts upon the stud 210 with the result that the side abutments 154, as well as the front and rear abutments 158, 156 are moved apart. As the carriers 190, 192 are rotated clockwise, as viewed in Fig. 4, under the action of the springs 204, 202, the tread end portion of the heel is first positioned transversely upon the platen 106 by the side abutments 154 and thereafter lengthwise upon said platen by the breast and rear abutments 158, 156, the shoulder 212 of the carrier 190 being moved away from the stud 210. Whenever it is inconvenient to open up the side abutments 154 and the breast and rear abutments 158, 156 by the use of the handle 214, the operator moves said abutments to their open positions by forcing the rear face of the heel against the face 188 of the rear abutment 156, such face depending below the heel engaging faces of the associated abutments for such purpose.

As will be explained later, in order initially to set up the machine to form in a separate operation passages or bores 216 (Fig. 6) in top lifts 218 of heels 20 after the passages 26 have been formed in the heels, it is desirable to provide adequate means for holding the heel abutments 154 and the breast and rear abutments 158, 156 in their retracted or open positions. Accordingly, there is pivotally mounted upon a bearing stud 220 (Fig. 4) threaded into the plate 106 a latch 222 which, when the rear abutment 156 has been moved to its open position, engages a face 224 of the guide block 180 thus retaining the side abutments 154 as well as the breast and rear abutments 158, 156 in their retracted or open positions against the action of the springs 202, 204.

The platen 142 has associated with it breast and rear abutments 226, 228 slidable along elongated slots 230, 232, respectively, a common longitudinal axis 234 (Fig. 5) of which is disposed at right angles to the axis 236 of the bearing pins 136 said axis 236 being parallel to the axis 164. The axis 236 extends along a work engaging face 238 (Figs. 2 and 3) of the platen 142.

The breast and rear abutments 226, 228 have work engaging faces 240, 242 (Figs. 3, 5 and 6). The breast abutment 226 is secured by a screw

239 and a shoulder screw 241 to a guide block 243 slidable along the slot 230. Slidably fitting in the slot 232 is a guide block 244 which is secured by a screw 246 and a shoulder screw 248 to a retaining portion 250 of the abutment 228. The collar 148 of the platen 142 has rotatably mounted on it a carrier 252 having a pair of arms 254 (Figs. 3 and 5) which are operatively connected through links 256 and the shoulder screws 241, 248 to the breast and rear abutments 226, 228. When the machine is operating upon Cuban work there is usually no need of adjusting the rear abutment 228 with relation to the retaining portion 250 and accordingly said abutment and retaining portion may be formed integral. In order, however, to adapt the machine for varying, in operating upon Louis work, the positions of the slots 24 lengthwise of the attaching face of the heel the rear abutment 228 and the retaining portion 250 are formed as separate parts so that the rear abutment may be adjusted with relation to said retaining portion. The rear abutment 228 is provided with a slot 258 extending parallel to the slot 232 and is initially secured manually in different adjusted positions along a channel 260 of the retaining portion 250 by a setscrew 262 which passes through the slot 258, is threaded into said retaining portion, and has a shoulder bearing against the abutment 228.

The breast and rear abutments 226, 228 are constantly urged to their open positions determined by the outer ends of the slots 230, 232 by a spring 264 opposite ends of which are attached to a stud 266 carried by the platen 142 and to a pin 268 pivotally connecting one of the arms 254 of the carrier 252 to a corresponding link 256. The work engaging face 242 of the rear abutment 228 is slightly concave and is constructed and arranged to engage the rear portion of the rim 58 of the attaching face 22 of the heel 20, the work engaging face of the breast abutment being beveled and relatively wide so as to engage the opposite upper breast edges of the Cuban heel or the forward edge of the lip of the Louis heel.

In order to move the breast and rear abutments 226, 228 to their closed heel orienting and clamping positions against the action of the spring 264, the retaining portion 250 of the rear abutment 228 has secured to it a handle 270 which may be grasped by the operator to move said abutments toward each other and against the heel thus causing the platen 142 to be freely tilted about its axis 236 while the heel is being oriented and positioned lengthwise upon the surface 238 of the platen. The abutments 154 which engage the sides of the heel 20 near its tread face 54 are relied upon to centralize the tread and attaching faces of the heel widthwise. The retaining portion 250 of the rear abutment 228 extends laterally beneath a roll 272 which forms a part of a Horton clutch 274 and is arranged in a bifurcation 276 of the lower end of a lever 278 fulcrumed on a pin 300 carried by an upstanding lug 302 secured by screws 304 to the platen 142, said lever being constantly urged counterclockwise, as viewed in Fig. 3, by a spring 306.

Preparatory to operating upon the shoe the operator depresses the treadle 120 to lower or effect translatory movement of the platen 142 with relation to the platen 106, the heel being presented to the machine with its tread face 54 upward. When the tread face 54 of the heel has been brought into engagement with the surface 160, 162 of the platen 106 and has been positioned lengthwise and widthwise with relation to the

axis 36 by the side, breast and rear abutments 154, 158 and 156 the operator removes his foot from the treadle causing upward translatory movement of the platen 142 and accordingly the surface 238 of such platen to be moved under spring pressure against the rim 58 of the attaching face 22 of the heel 20. The handle 270 is then moved rearward, that is to the left as shown in Fig. 3, causing the spaced platens 106, 142 to be independently and freely tilted about their parallel axes 164, 236 as the attaching face of the heel is positioned upon the platen 142 lengthwise with relation to the axis 36 by the front and rear abutments 226, 228. The roll 272 of the Horton clutch constantly engages a face 308 of the retaining portion 250 of the rear abutment 228 and an inclined wedge face 310 of a plate forming part of the lug 302, the construction and arrangement being such that the rear abutment 228 is permitted to move rearward, that is, to the left as viewed in Figs. 3 and 5, but when the spring is released, is held against retractive movement by the roll which is forced with binding pressure against the face 308 by reason of action against it of the wedge face 310. After the heel 20 has been positioned and clamped, as viewed in Fig. 3, the arm 38 of the drill 34 is turned clockwise as viewed in Fig. 1 to depress the drill through the positioned and clamped heel to form the passage 26. The arm 38 is then swung counterclockwise to raise the drill to starting position and the heel is removed from the machine.

It is desirable from the standpoint of economy to form the passages 26 in the wood heels 20 in wood heel turning plants but this necessitates subsequent drilling through the top lift 218 of the covered heel, the passage 216 being in register with the passage 26. Covered heels having top lifts attached to them may if desirable be drilled to form in one operation the combined passage 26, 216. It is also contemplated, after covering the heels and applying the top lift 216 thereto, to form in one operation the passages 26, 216 of the heels, the passages 26 commonly stopping just short of the attaching faces 22 of the heels and the slots which are formed in said attaching faces during a subsequent operation, breaking through the inner ends of the passages 26. The downward extents of the passages 26 formed by such modified practice are determined by an initially adjustable stop (not shown) with which the drill actuating arm 30 engages.

When it is desirable to equip the machine to operate upon heels having top lifts 218 so as to form the passages 216, there is inserted in a recess 312 of the yoke or carrier 112 a pin or spindle 314 (Fig. 6), said pin being secured to the yoke by a setscrew 316. After the treadle 120 has been depressed to lower the platen 142 the covered heel 20 in which the passage 26 has been formed and to which the top lift 218 has been attached is placed on the pin 314 with the pin fitting in the passage and the covered rim 58 of the attaching face 22 of the heel resting upon the surface 238 of the platen 142, the breast and rear abutments 226, 228 being held in their open positions by the spring 264, and the side breast and rear abutments 154, 158 and 156, respectively, being held in their open positions by the above described latch 222 which when in its operative position engages the face 224 of the block 180 of the rear abutment thus preventing such abutment and through it, the side and breast abutments, from moving to their closed positions under the action of the springs 202, 204. The

axis of the pin 314 positioned in the drill jig 56 is in alinement with the axis 36 of rotation and reciprocation of the drill 34. When pressure against the treadle 120 is released the platen 142 is raised by the spring 130, forcing the top lift 218 against the face 160, 162 of the platen 106, the heel if necessary rotating slightly under pressure of the plates to move the median heightwise plane of the heel into a position in which it extends forward and rearward of the machine as shown in Fig. 6. The operator then rotates the arm 38 (Fig. 1) clockwise to lower the drill 34 thus forming in the top lift 218 of the heel the passage 216 which is in alinement with the previously formed passage 26 in the heel. After raising the drill 36 the treadle 120 is again depressed preparatory to removing the heel from the machine.

Having thus described our invention, what we claim as new and desire to secure by Letters Patent of the United States is:

1. In a heel drilling machine, a pair of spaced independently and freely tiltable platens mounted for relative translatory movement to clamp between them any one of a plurality of heels of different sizes and styles, means for orienting independently upon said platens with relation to a fixed axis the tread and attaching faces respectively of said heel, and a drill movable lengthwise of said axis to form in the heel a passage extending lengthwise of the heel.

2. In a heel drilling machine, a frame, guides secured to said frame, a platen mounted for free pivotal movement upon the frame, a second platen which is mounted upon said frame for free pivotal movement with relation to the first-named platen and is also mounted for translatory movement upon the frame toward and away from the first-named platen and generally lengthwise of said guides, means for moving independently into predetermined positions the tread and attaching faces of a heel upon the first and second named platens respectively, a drill movable lengthwise of said guides, and means for operating said drill to bore a hole in said heel.

3. In a heel drilling machine, a pair of platens which are mounted for independent and free pivotal movement about parallel axes, respectively, and are constructed and arranged to be engaged by the tread and attaching faces respectively of a heel, means for effecting relative translatory movement of the platens in a path disposed approximately at right angles to said axes; a rotatable drill which is movable in a rectilinear path disposed at right angles to the axes; sets of gages for independently positioning the tread and attaching faces of the heel upon the platens respectively; and means for operating the drill to form a passage extending heightwise of the heel.

4. In a heel drilling machine, a rotatable drill, means for rotating the drill about an axis, means for reciprocating the drill lengthwise of said axis, a pair of platens having faces constructed and arranged to be engaged respectively by the tread

face of a heel and the rim of the attaching face of the heel, said platens being independently and freely tiltable about parallel axes which lie approximately in said faces respectively of the platens and which establish a plane including the axis of rotation of the drill, means for effecting relative translatory movement of said platens as their axes of rotation remain in said plane to cause the platens and the heel to be forced together, and means for independently sliding the tread face of the heel and the rim of the attach-

ing face of the heel then into forced engagement with the platens into predetermined positions upon said platens.

5. In a drilling machine, a jig for positioning and clamping any one of a plurality of heels of different sizes and styles, said jig comprising a pair of platens having heel engaging surfaces respectively, said platens being independently and freely tilttable about parallel axes which lie in said surfaces respectively and establish a plane, means for effecting relative translatory movement between the platens while their axes remain in said plane and in parallel relation to each other to cause top lift receiving and attaching faces of the heel being operated upon to be forced against said surfaces of the platen, and means for independently centralizing said faces of the heel upon said surfaces of the platens.

6. In a drilling machine, a jig for positioning and clamping any one of a plurality of heels of different sizes and styles, said jig comprising a pair of platens having heel engaging surfaces respectively, said platens being independently and freely tilttable about parallel axes which lie in said surfaces respectively and establish a plane, one of said platens being movable toward and away from the other while the axis about which it is tilted remains in said plane and parallel to the axis about which the other platen is tilted, and a spring for constantly urging said one platen toward the other to cause said surfaces of the platens to be forced against top lift receiving and attaching faces of the heel.

7. In a drilling machine, a jig for positioning and clamping heels to be drilled, a drill, said jig comprising a guideway for the drill, a pair of platens which have holes in alinement with said guideway and which have opposed surfaces constructed and arranged to be engaged by the tread face of a heel and the rim of the attaching face of the heel respectively, said platens being independently and freely tilttable about parallel axes which lie approximately in said surfaces, means for effecting relative rectilinear movement between the platens while the axes about which the platens are tilttable remain in parallel relation to cause forced engagement of the tread face and the rim of the attaching face of the heel with said surfaces of the platens as said faces of the heel bridge the holes of the platens, means for independently orienting with relation to said guide the tread and attaching faces of the heel forced against said surfaces of the platens, and means for operating the drill along said guideway and through said holes to form a passage extending heightwise through the heel.

8. In a heel drilling machine, a pair of platens which are pivoted for movement about parallel axes and which have surfaces constructed and arranged to be engaged respectively by the tread face and the rim of the attaching face of a heel, a drill rotatable about an axis which lies in the plane of said axes and is disposed at right angles to said axes, side gages on the one hand and breast and back gages on the other hand independently movable along said surface of one of said platens, springs for urging the side gages on the one hand and the breast and rear gages on the other hand toward each other to orient the tread end of the heel on said surface of said one platen, means for effecting relative translatory movement of the platens to effect forced engagement between the tread face and the rim of the attaching face of the heel and said surfaces respectively of the

platens, breast and rear gages slidably mounted for movement toward and away from each other upon the other of said platens, a spring for constantly urging said breast and rear gages of said other platen away from each other, manually actuated means for moving the breast and rear gages of said other platen toward each other against the action of said last-named spring to centralize the attaching face of the heel on said surface of said other platen, a clutch for locking said manually operated means against movement to secure said breast and rear gages in their heel centralizing positions upon said other platen, and means for moving the drill in a rectilinear path extending lengthwise of its axis to form in the heel a passage extending lengthwise of the heel thus positioned and clamped.

9. In a heel drilling machine, a drill, means for rotating the drill about and for moving it lengthwise of a fixed axis, a pair of platens which are independently tilttable, a spindle extending through one of the platens and adapted to be received in a passage formed in and extending generally heightwise of a heel to which a top lift has been attached, said spindle having an axis which is in substantial alinement with the axis of the drill, and means for effecting a relative movement lengthwise of said axis between one of the platens on the one hand and the other of the platens and the spindle on the other hand to move the heel to a predetermined position and to clamp it in such position, said drill, upon its rotation about and movement lengthwise of said axis, forming in the top lift of the heel a passage which registers with and is a continuation of the passage in the heel.

10. In a machine for drilling heels, a pair of platens mounted for independent pivotal movement about parallel axes respectively, a spindle constructed and arranged to be received in a passage extending heightwise of a heel to which a top lift has been attached, means for effecting relative movement of translation between the platens to effect forced engagement between one of the platens and the rim of the attaching face of the heel on the one hand and between the other platen and the tread end of the top lift of the heel on the other hand to orient the heel upon the spindle and to clamp it to the platens, and a drill movable in a rectilinear path through the top lift and into said passage to form in said top lift a continuation of said passage.

11. In a machine for drilling heels, a rotary drill, a guide having a drill receiving and guiding cylindrical bore, a pair of platens independently pivoted about parallel axes which are disposed at right angles to an axis of said bore and intersect such axis, a spindle which is constructed and arranged to be received in a passage extending heightwise of a heel to which a top lift has been attached, said spindle having an axis which is in alinement with the axis of the bore of the guide, means for effecting relative translatory movement between the platens to cause said platens to be forced against the rim of the attaching face of the heel and the tread end of the top lift of the heel to position said heel upon the spindle and to clamp it against movement, and means for moving the drill along said bore and through the top lift and into the passage of the heel to form in said top lift a continuation of said passage.

12. In a heel drilling machine, a drill, means for rotating the drill about an axis and for reciprocating it in a rectilinear path extending lengthwise of said axis, a pair of platens which

11

are independently pivoted about parallel axes defining a plane including the axis of rotation of the drill and which have surfaces one of which is constructed and arranged to be engaged by the rim of the attaching face of a wood heel having 5 formed in it a passage extending heightwise thereof and the other of which surfaces is constructed and arranged to be engaged by the tread face of a top lift forming part of the heel, a spindle constructed and arranged to receive the wood heel by engagement in a preformed passage in the heel, a carrier for one of the platens and the spindle, means for operating the carrier to cause the tread end of the top lift of the heel upon the spindle to be forced against said surface of said other platen and to cause said surface of said one platen to be forced against the rim of the attaching face of the heel, said platens and spindle co-

10 5 operating to locate and hold against movement the heel in a predetermined position, and means for reciprocating the drill, said drill when reciprocated in said rectilinear path forming in said top lift a passage which registers with the pre-

formed passage of the wood heel.
